UNITED STATES PATENT OFFICE.

HAROLD BREADY WEAVER, OF NEW YORK, N. Y., ASSIGNOR TO AMERICAN MOTORBUS CORPORATION, A CORPORATION OF NEW YORK.

OMNIBUS.

1,312,288.

Specification of Letters Patent.

Patented Aug. 5, 1919.

Application filed May 15, 1917. Serial No. 168,638.

To all whom it may concern:

Be it known that I, HAROLD B. WEAVER, a citizen of the United States, residing at New York, in the county of New York and State 5 of New York, have invented certain new and useful Improvements in Omnibuses, of which the following is a specification:

This invention relates to omnibuses and particularly to the body or car of a double 10 deck motor omnibus wherein the passengers are carried on two floors one above the other. The object of the invention is to provide for seating a maximum number of passengers for the size of the body and at the same time 15 to permit rapid and safe entrance and exit of the passengers to and from both decks of the vehicle. The increased number of seats means greater earning capacity at all times while the more rapid exit and entrance of 20 the passengers reduces the time lost in stops and increases the daily mileage of the car.

In prior omnibuses much of the available seating space is wasted in the arrangement and construction of the stairs and passages 25 and the disposition of the seats and some of the seats inconveniently face rearward so that the passengers in them ride backward. In prior structures, moreover, the stairways to the upper deck are so constructed as to 30 compel the passengers to traverse them in the direction of the movement of the vehicle so that the starting or stopping of the car tends to throw the passengers off their balance forward or backward on the stair- 35 way steps in a very dangerous manner compelling them to cling to the handrails to avoid falling and making the use of the stairs, while the car is in motion, difficult and unsafe. This increases the allowable time 40 for acceleration and deceleration of the car and greatly lengthens the time of the stops as many passengers to or from the upper deck either will not venture on the stairs, while the car is in motion, or are so impeded 45 in getting down the stairs that they do not reach the lower floor until a considerable time after the omnibus has come to a stand- still.

In the construction of this invention a 50 maximum number of seats are provided for the size of the car and none of the seats face rearwardly. The stairway to the upper deck is completely inclosed and extends trans- versely of the car so that the passengers on 55 it easily accommodate themselves to the starting and stopping of the car by simply

leaning to one side or the other against the side walls of the stairway. The turn from the stairway at each deck is made so that the passengers are fully protected against mis- 60 steps or falling on any part of their travel from one floor to the other. At the same time the passageways and seats of each deck are so disposed as to offer a minimum hindrance to the movement of the passengers 65 and a large roomy entrance space is pro- vided permitting the entering and discharg- ing passengers from and to both decks to easily pass each other and allowing the om- 70 nibus to be started while the fares are still being collected on the pre-payment plan. By these improvements the omnibus is not only rendered more convenient and acces- 75 sible to the passengers, but its carrying and consequently its earning capacity are in- creased for each trip and the number of trips that can be made each day is increased by the shortening of the periods of stopping and the higher allowable rate of acceleration and deceleration at each stop.

In the accompanying drawings,

Figure 1 is a side elevation of an omnibus showing one embodiment of this invention with parts broken away to disclose the construction within;

Fig. 2 is a plan view of the omnibus looking down on the upper deck;

Fig. 3 is a plan view of the lower deck;

Fig. 4 is a rear view of the omnibus with parts broken away to show the construction 90 within; and

Fig. 5 is a front view of the omnibus shown in Fig. 1.

In the embodiment of the invention shown in the drawings, 1 is an omnibus body sup- 95 ported low close to the ground on the rear wheels 2 and front steering wheels 4 of the truck 6. In the preferred form shown, this front truck is a detachable tractor both driv- ing and steering the vehicle and it is nar- rower than the car body 1 so that on each side front windows 7 give the passengers a direct view ahead. The rear wheels 2 are positioned within the contour of the car per- 100 mitting close approach to the curb and in the low construction shown providing a conven- ient, "stepless" entrance for the passengers.

The entrance door 10 is positioned near the rear end of the car and behind the rear wheels 2 giving a properly balanced con- 110 struction and making the entrance safer, as a misstep at the door will not throw the pas-

passenger in front of the wheels. A large entrance space 11 is provided within, permitting easy ingress and egress of passengers to or from each deck and allowing the conductor to control the door and to collect the fares of the incoming passengers for both decks as they enter. Immediately after entering, the passengers separate into those going to the upper deck by the stairway 12 at the extreme rear of the car, or those going to the seats of the lower deck by the aisle 13. Along this aisle the seats may be arranged in any desired manner but preferably as shown so that the lower deck is provided with two rows of double seats 15 all facing forward and at the wheel boxes 16 single seats 17 also facing forward. Opposite the entrance are positioned the three seats 18 all facing forward and one seat 19 facing transversely of the car. The lower deck is, therefore, so constructed as to provide not only generous entrance and aisle space, but also to house the wheels within the contour of the car and yet have a maximum number of twenty-two seats, all but one facing forward.

The stairway 12 is housed within the sides of the car and comprises a series of steps 21 leading transversely across the back of the car from a landing 20 flush with the lower deck to the upper deck 24 making the turn at the upper deck by the large landing platforms 22 and 23. By this construction a passenger on the stairs 21 faces transversely of the direction of motion of the vehicle, is not thrown lengthwise of the stairs by the slowing down or speeding up of the vehicle and may easily accommodate himself to the starting or stopping of the vehicle by simply leaning against the solid partitions 25 and 26 at either side. The lower landing 20 provides a stepless entrance to the stairs 21 from the lower floor and the upper landing platforms 22 and 23 are not only large, but are provided with the high protective sidings 27 and 28 as well as the post of the fencing 29 so that the passenger is at all times surrounded by a high protecting wall against which he can lean his weight as urged by the movement of the car. The lowest step 21 and the upper landing 23 both face transversely of the car so that the entire travel of the passenger to and from the upper deck is in a direction transverse to the movement of the vehicle except in stepping between the large safe landing platforms 22 and 23, and at this point, and all points in his travel, the passenger is protected by the high surrounding walls enclosing the stairway and platforms. The ease and safety of the passage to and from the upper deck enables and encourages the passengers to travel these steps while the vehicle is in motion so that time is not lost at the stopping points waiting for the passengers to descend from the car at the upper deck. This construc-

tion has been attained without loss of space and with an actual improvement in the type of stairway used. For, in place of the confusing spiral stairway so common in omnibus construction, an ordinary straight stairway and landings are used, fitting snugly across the rear end of the car and permitting a disposition of the seats on both decks to attain a maximum seating capacity and at the same time provide readily accessible passages.

The transverse stairway leaves one side of the upper deck uninterrupted and arrives at the upper deck well to one side of the aisle 33. Just in front of the landing 23 is positioned the single side seat 31 leaving a large space 34 at the approach to the stairway for the passengers waiting to go down. The seats from the aisle 33 may be arranged in any desired manner. In the preferred construction shown, the two rows of double seats 30 all facing forward are placed at the sides of the deck, giving a maximum number of forward facing seats for the space occupied. Within the standard overall length of the omnibus which is about twenty-five feet, this invention, therefore, provides forty-nine forward facing seats and two side seats so that fifty-one passengers in all are seated, representing a substantial advance over any prior construction both in the number of seats and their convenience.

At the same time easy access is afforded to every seat. Large spaces are provided at each landing of the stairs 21 and each end of the stairway is visible from the other through or over the netting 29. The large entrance space 11 permits the passengers to collect for quick exit and allows the door to be closed and the omnibus started while fares are still being collected on the pre-payment plan. In placing the turn of the stairway at the extreme upper end, large head room is left over seats 18 and 19. By the transverse inclosed stairway the passengers may go safely and quickly to or from the upper deck while the car is in motion. The omnibus is, therefore, made not only easily and safely accessible to the passengers, but the time consumed at each stop is greatly reduced and the daily mileage is correspondingly increased.

It is apparent that other driving means for the omnibus may be used and the invention is not confined to the specific embodiment shown and described, but is intended to cover such modifications thereof as fall within the scope of the appended claims.

Having thus described my invention, I declare that what I claim as new and desire to secure by Letters Patent, is:

1. In a double deck motor omnibus, the combination with an upper deck and a lower

- deck having inclosing sides extended above said upper deck, of a transverse stairway within the inclosure of said sides comprising a substantially straight flight of stairs starting from the lower deck and extending transversely across the body of the omnibus, and a pair of landing steps within said inclosing sides and making a 180° turn to terminate at the upper deck in a central 5 landing space in a direction transverse to the body and protecting siding making a 180° turn to said top central landing platform so that the approach to said stairway will be transverse of the direction of movement of 10 the omnibus and the passengers traversing said steps will be protected by the inclosing sides.
2. In a double deck motor omnibus, the combination with a lower and an upper 15 deck, of an entrance door at one side of said lower deck, a stairway leading from the door side of the lower deck to the opposite side of the upper deck and comprising a flight of steps extending transversely across 20 the body of the omnibus and upper step landings making a 180° turn to a central landing platform and protecting siding making a 180° turn to said top central landing platform, so that the starting or stopping of the 25 omnibus does not tend to throw a passenger on said steps lengthwise thereof at any point and the passengers approach and leave said stairway in a direction transverse to the line of movement of the omnibus and 30 are protected by siding or railing throughout the length of the stairway.
3. In a double deck motor omnibus, the combination with a lower and an upper deck, of an entrance door at one side of said 35 lower deck, a stairway leading from the door side of the lower deck to the opposite side of the upper deck and comprising a flight of steps extending transversely across the body of the omnibus and upper step 40 landings making a 180° turn to a central landing platform, so that the starting or stopping of the omnibus does not tend to throw a passenger on said steps lengthwise thereof at any point and the passengers approach and leave said stairway in a direction 45 transverse to the line of movement of the omnibus, a transverse forward facing 50
- seat on said upper deck above said stairway, and a second seat on said upper deck immediately adjacent the topmost landing step. 55
4. In a double deck motor omnibus, an inclosed stepless lower deck and an upper deck, a side entrance to said lower deck in back of the rear wheels of the omnibus, lower deck seats in front of and opposite 60 said entrance, a lower stairway landing in rear of said entrance space, a transversely extending stairway leading from said landing to the upper deck, and seats on said upper deck including a seat over the lower end of 65 said transverse stairway.
5. In a double deck motor omnibus, the combination with an inclosed lower deck and an upper deck, of rows of forward facing 70 seats on each of said decks, an entrance door on said lower deck, an entrance space within said door, an aisle leading from one end of said entrance space and extending between said rows of seats on said lower deck, seats at the side of said entrance space opposite 75 said door, a stairway within the inclosure of said lower deck at the other end of said entrance space and comprising a transversely extending flight of stairs having a turn at their upper end over said seats in said entrance space. 80
6. In a double deck motor omnibus, the combination with an inclosed, stepless lower deck and an upper deck, of a row of forward facing 85 seats on each side of said lower deck, an aisle between said rows of seats and leading rearwardly to an entrance space, seats on one side of said entrance space and a door on the other side thereof, a stairway in the rear of said entrance space leading transversely across the back of said lower deck 90 and terminating at one side of said upper deck in a turn positioned above said seats in said entrance space, a row of forward facing double seats extending the full length 95 of the other side of said upper deck, and a row of forward facing double seats extending along the side of the upper deck to which said stairway leads and terminating in a transversely facing seat which leaves a wide 100 space on the upper deck for approach to said said stairway.

HAROLD BREADY WEAVER.
